WEAVER'S SHUTTLE

Rudolf Schmidt, Passeck-on-the-Iser, Germany;
vested in the Alien Property CustodianApplication October 15, 1941, Serial No. 415,025
In Germany June 5, 1940

3 Claims. (Cl. 139—210)

1

The known constructions of loom shuttles with hinged two-armed shuttle peg frequently have the drawback that the pirn or spool cannot be held fast on the peg quite safely, because the arms of the peg which approach one another by elastic forces present only a comparatively small elastic force for holding fast the pirn, this fact being due to the length of the arms. It is an object of the invention to improve the support of the pirns on the shuttle peg. According to the invention the arms of the shuttle peg are kept apart by a helical spring arranged between the two peg arms near the hinge or pivot of one or both peg arms on the loom shuttle. Because of the mutual support of the ends of the peg arms a strong elastic action between the peg arms can be obtained even by a comparatively small helical spring, this action being quite sufficient for holding fast the pirns on the shuttle peg with ample forces. For, it is an advantage of the construction according to the invention that the elastic force due to the inserted helical spring, is acting just on a point where the spreading force between the peg arms for holding fast the pirns, has the required effect. Nevertheless this spreading force always has the necessary elasticity to prevent breaking of the pirns (for instance with wood pirns) or to prevent an undesired deformation (for instance with paper pirns). In order to permit the removal of the pirn from the peg provided with supporting surfaces, an abutment is provided for the free end of that peg arm which is not hinged in the shuttle, this abutment permitting the two peg arms to press against one another when the same are raised. According to the invention this abutment may have the form of an inclined gliding or guiding surface for the end of the free peg arm acted upon by the spring, the free end of this arm bearing upon the gliding or guiding surface in such a manner that the peg is held fast, when the peg is lowered, by the action of the helical spring inserted between the two peg arms.

The drawing shows a device according to the invention by way of example. In Figure 1 a section is represented through that portion of a shuttle where the two armed peg is hinged, showing the mutual support of the peg arms according to the invention; Figs. 2 and 3 represent other modifications of the device according to the invention.

In the hollow part 1 of the shuttle 2 the peg comprising two arms 3 and 4 is hinged by way of a bolt 5, around which the peg arm 3 can be

2

turned. The peg arms 3 and 4 are connected with one another at the end 6. In the neighbourhood of the pivot 5 a recess 7 is provided in the peg arm 3, a helical spring 8 being placed in the recess bearing against the free end 9 of the peg arm 4 so that the two peg arms are kept apart in elastic manner. The peg arm 4 is provided with an abutment 10 for holding fast the pirn set upon the peg. The free end 9 of the peg arm 4 cooperates with the inclined gliding or guiding surface 11 which advantageously is made of a metal plate secured to the shuttle body by means of a pin 12. The bolt 13 serves to limit the lowering movement of the peg.

15 On turning the peg in the shuttle just described, out of the hollow space 1 to such an extent that the free end 9 of the peg arm 4 bears against the surface 11, the pirn can be set or removed, respectively, without any difficulty. 20 However, in the lowered position slipping of the pirn from the peg is wholly prevented because the two peg arms are pushed apart by the spring 8 so that the pirn is held fast by the elastic force of the peg arms and moreover by the abutment 25 10. The gliding or guiding surface 11 not only serves the purpose of pressing the two peg arms against one another to enable shifting of the pirn, but also in the constructional form shown in Fig. 1 holds fast the peg and thereby also the 30 pirn in the lowered position. The peg arm end 9, pushed upward by the spring 8, bears upon the gliding or guiding surface 11 in such a manner that raising of the peg could be effected only by pressing the spring 8 i. e. with a comparatively great force. As Fig. 1 shows, the force 35 which has to be overcome on raising the peg is at a maximum on the beginning of the raising movement and decreases during this movement. From this fact the advantage results that the 40 peg is held fast with a very great force when the peg is in lowered position i. e. during the time of working.

If the free peg arm 4 has only to hold fast the pirn and does not serve to fix the peg in the lowered working position, constructions as shown by 45 way of example in Figs. 2 and 3 may be recommended. Fig. 2 shows a construction of the peg wherein a leaf spring 14 (or the like), which is arranged separately from the free peg arm 4, is connected with the peg arm 3 and projects with its free end 15 towards the inclined gliding or guiding surface 11. The end 15 of the leaf spring 14 bears against helical spring 16 in the same manner as the free end 9 of the peg arm 4 against the spring 8. In order to prevent interference

between the peg arm 4 and the leaf spring 14 the peg arm 4 passes through an aperture 17 of the leaf spring 14. The function of the shuttle corresponding to Fig. 2 is analogous to that of Fig. 1 with the difference that the two objects, viz. holding fast of the pinn and fixing of the peg in the lowered position are distributed in the constructional form shown in Fig. 2 to the peg arm 4 and the leaf spring 14, whereas in the constructional form according to Fig. 1 both objects are fulfilled by the peg arm 4 alone.

According to Fig. 3 an arm 18 advantageously Z-shaped is provided, said arm being pivoted at one end upon a bolt 19 and at the other end bearing against a helical spring 20. This arm 18 cooperates with corresponding planes on the bearing 21 so that the peg is kept fast in the raised, as well as in the lowered position. In this constructional form the free peg arm 4 also serves only the purpose of keeping the pinn fast on the peg. The pinn can be removed from the peg when the peg is in the raised position by pressing the free peg arm end 9 against the vertical part 22 of the arm 18.

What I claim is:

1. In a loom shuttle having a hollow space therein, a peg arm having one end thereof hinged to said shuttle within said space, a second peg arm secured to the free portion of said first arm and extending alongside the first arm in the direction of said hinge, a helical spring arranged between the peg arms in the vicinity of said hinge, a leaf spring extending substantially parallel to and having one end thereof secured upon said hinged peg arm, a second helical spring arranged between the hinged peg arm and the free end of said leaf spring, and a gliding surface cooperating with the free end of said second peg arm through the medium of said leaf spring, said gliding surface being inclined relative to the longitudinal axis of the leaf spring and adapted to hold said peg arms in lowered position within said hollow space.

2. In a loom shuttle having an elongated spindle cavity therein, an elongated spindle pivoted

at one end thereof in said cavity, means for limiting the downward rotation of said spindle about said pivot when the spindle is in normal position within said cavity, a resilient arm extending from the free end of said spindle reversely toward said pivot, and abutment means provided with a substantially flat guiding surface against which the end of said arm slides while the spindle is rotated out of said cavity, said surface forming an acute angle with the upper portion of said arm, and the point of contact of said arm with said surface lying on a line disposed at right angles to the surface and passing above said pivot, whereby gradually decreasing resistance will be offered to the upward rotation of said spindle from its normal position within the cavity to a position outside the cavity.

3. In a loom shuttle having an elongated cavity therein, an elongated spindle pivoted at one end in said cavity, an arm having one end thereof attached to the free end of said spindle and extending reversely along said spindle, a spring normally urging said arm away from said spindle toward the open end of said cavity, means for limiting the inward rotation of said spindle about said pivot when the spindle is in normal position within said cavity, a second arm secured to the spindle at a point intermediate the hinge and the point of attachment of said first arm, said second arm extending reversely along said spindle and having the free end thereof interengageable with the free end of the first arm when the second arm is moved toward the spindle, a second spring between the free end of said second arm and said spindle, and abutment means provided with a substantially flat guiding surface against which the free end of said second arm slides while the spindle is rotated out of said cavity, said surface forming an acute angle with the side of the second arm facing the open end of said cavity, whereby the second arm is held against said second spring and said spindle is held against said limiting means within said cavity.

RUDOLF SCHMIDT.
